(57) **CLAIM**

The ornamental design for a roof mounted electrical service stanchion, as shown and described.

DESCRIPTION

FIG. 1 is a top perspective view of a roof mounted electrical service stanchion showing my new design;

FIG. 2 is an exploded perspective view thereof;

FIG. 3 is a front side view thereof;

FIG. 4 is a rear side view thereof;

FIG. 5 is a left side view thereof;

FIG. 6 is a right side view thereof;

FIG. 7 is a top side view thereof, and,

FIG. 8 is a bottom side view thereof.

The broken lines shown in FIG. 1 illustrate environment that form no part of the claimed design. The broken lines shown in FIG. 8 illustrate portions of the roof mounted electrical service stanchion that form no part of the claimed design.

1 Claim, 5 Drawing Sheets
